UNITED STATES PATENT OFFICE.

CHAUNCEY C. REHARK, OF CLEVELAND, OHIO.

DESIGN FOR A GAME APPARATUS.

57,062.

Specification for Design.

Patented Feb. 1, 1921.

Application filed March 22, 1920. Serial No. 367,881. Term of patent 14 years.

To all whom it may concern:

Be it known that I, CHAUNCEY C. REHARK, a citizen of the United States, residing at Cleveland, in the county of Cuyahoga and State of Ohio, have invented a new and original Design for Game Apparatus, of which the following is a specification, reference being had to the accompanying drawing, forming a part thereof, in which

The figure of the drawing is a plan view of a game apparatus embodying my design.

I claim:

The ornamental design for a game apparatus as shown.

CHAUNCEY C. REHARK.

Witnesses:

JOHN F. ROBB,
HUGH S. HILL.
